(57) **CLAIM**

The ornamental design for a cartridge packaging box, as shown and described.

DESCRIPTION

FIG. 1 is a front elevation view of a cartridge packaging box, showing our new design.

FIG. 2 is a rear elevation view thereof.

FIG. 3 is a left-side elevation view thereof.

FIG. 4 is a right-side elevation view thereof.

FIG. 5 is a top plan view thereof.

FIG. 6 is a bottom plan view thereof.

FIG. 7 is a front, left, and bottom perspective view thereof; and,

FIG. 8 is a front, left, and top perspective view thereof shown in a condition of use.

The broken lines in the figures illustrate portions of the packaging box that form no part of the claimed design.

1 Claim, 4 Drawing Sheets
